UNITED STATES PATENT OFFICE.

GEORGE JAMES GAWLEY, OF FLEET, ENGLAND.

APPARATUS FOR DISCHARGING FLUIDS OR BODIES FROM CONTAINERS.

1,256,305.

Specification of Letters Patent. Patented Feb. 12, 1918.

Application filed April 24, 1916. Serial No. 93,292.

To all whom it may concern:

Be it known that I, GEORGE JAMES GAWLEY, a subject of the King of Great Britain, residing at Kent House, Fleet, Hampshire, 5 England, have invented new and useful Improvements in Apparatus for Discharging Fluids or Bodies from Containers, of which the following is a specification.

My invention relates chiefly to apparatus 10 for discharging liquids, under pressure, from a reservoir or container, the invention being especially applicable for use in connection with fire extinguishers, although it can be applied in other cases in which it is desired to deliver a liquid, gaseous or other body from a tank or container in which it is stored, and according to my invention I provide for utilizing the ordinary pressure of the atmosphere for the purpose.

20 To enable the invention to be fully understood I will describe the same by reference to the accompanying drawings, in which:—

Figure 1 is a sectional view illustrating the application of my invention in its simplest form to a syringe.

Figs. 2 to 9 illustrate the application of my invention to a portable apparatus for use as a fire extinguisher, Fig. 2 being a longitudinal section of such apparatus, Figs. 30 3 and 4 views of the upper and lower ends of the said apparatus, Figs. 5, 6 and 7 sections on the line 5—5, 6—6 and 7—7 respectively of Fig. 2, Fig. 8 a section on the line 8—8 of Fig. 4, and Fig. 9 a view somewhat 35 similar to Fig. 2, but showing the position of the parts when the apparatus is filled with liquid ready for discharge.

Figs. 10 to 12 illustrate a further modification.

40 The arrangement of my invention shown in Fig. 1 comprises two cylinders A, B which respectively contain pistons A¹, B¹, the rods of the said pistons being connected by a handle C. The cylinder A is at one end 45 closed against the pressure of the atmosphere while the other cylinder B is provided with an ordinary nozzle D. With this arrangement it will be understood that when by means of the handle C, the two pistons are 50 drawn out simultaneously in their cylinders, the cylinder B can be filled with liquid while a vacuum will be formed beneath the piston in the cylinder A. When the pistons are released the atmospheric pressure acting

upon the top of the piston A¹ will cause the 55 movement of the piston B¹ to eject the liquid from the cylinder B.

In the arrangement illustrated in Figs. 2 to 9 a cylinder is divided into two parts by a partition, each of which parts contains a 60 sliding piston, the said pistons being connected together tandemwise, so that they move simultaneously. One of these chambers is adapted to have a vacuum formed in it while the other is designed to receive 65 water or other liquid, orifices being provided for the admission and escape of the air behind both of the pistons and also an orifice in the liquid chamber for the admission and discharge of the liquid. Means are 70 also provided for locking the pistons against the action of the vacuum.

In these figures a indicates the vacuum cylinder and b a piston sliding therein, the said cylinder having the end c completely 75 closed so as to preclude the admission of air. d is the liquid container which, as shown, is made slightly larger than the cylinder a, but attached thereto, and having arranged within it a piston e which is directly connected 80 with the piston b by the rod e¹. d² is an orifice in the end wall d¹ on the cylinder d which serves to allow the passage of air to and from one side of the piston e.

The two cylinders a and d are separated 85 by a partition f having in it a stuffing-box through which the rod e¹ slides and which stuffing box serves to prevent leakage from the cylinder d. The cylinder d has in it the elbow pipe f¹ which projects through the 90 partition f and which serves to admit atmospheric air into contact with the piston b and also for the ejection of air from the cylinder a and the said cylinder d has also connected with it the pipe g through which 95 the cylinder d is filled with liquid and through which such liquid is also discharged.

h is an extension rod which forms a part of the piston rod e¹ and which serves for operating the pistons b and e, the said extension rod being made detachable from the rod e¹ for a purpose hereinafter described.

The extension rod h is screw-threaded and has mounted upon it a nut i to which a hand wheel i¹ is fixed, the said nut having 105 a flange i² which can turn and slide within a socket j on the wall d¹ at the upper end of the cylinder d. The extension h is screwed

into a boss k secured to the upper side of the piston e and said boss has its upper portion forked to provide oppositely disposed vertical slots l^4 for a purpose hereinafter described. The sides of the boss k are provided with oppositely disposed notches k' which are engaged by spring pressed pawls k^2 , when the piston e is moved upwardly for the purpose of locking the pistons in raised position. These spring pressed pawls k^2 are mounted for horizontal sliding movement in the lower part of the socket j and their adjacent ends are provided on their under sides with inclined portions which are engaged by the upper end of the boss k , when the boss is raised to force the pawls away from each other and hold them in this position until the notches k' are opposite the pawls, when said pawls will move toward one another under the action of their springs to lock the pistons in raised position.

Mounted within the socket j between the nut i^2 and pawls k^2 , is a disk l provided on its underside with oppositely disposed downwardly extending lugs l' having inclined outer faces which enter the slots l^4 in the boss k when the boss is raised. The disk l is held in raised or inoperative position by means of a spring l^3 and when it is desired to release the pawls k^2 from the notches k' , this disk is moved downwardly by exerting pressure on the hand wheel i' , and as the disk moves downwardly the lugs l' will descend in the slots l^4 and the inclined outer faces of said lugs will engage the adjacent ends of the pawls k^2 and move them apart to permit the pistons to be released. In order to prevent the piston e from turning so that the said slots l^4 will be out of position with relation to the said lugs, the piston rod e^1 is made hollow and provided with a square guide m which slides upon a square rod m^1 attached to the cover c . The extremity of the hollow piston rod e^1 adjacent to the piston e is so closed so as to prevent the admission of the air.

At the outer end of the delivery tube g is inserted a plug g^1 having a central orifice 50 and over the said end of the tube g is screwed a nozzle g^2 having a plug g^3 drilled with orifices, one central hole at the outer end and two diverging holes therefrom. When the plug g^3 is screwed down on to the seating or face of the plug g^1 all access of air or liquid from or to tube g is prevented. At the extreme end of nozzle g^2 is a spray flap g^4 which when elevated by the milled head g^5 causes the jet from the plug g^3 to be sprayed. The extension of the head g^5 on the nozzle g^2 permits of the latter being easily turned in order to move the plug g^3 from or to its seating on the plug g^1 .

The operation of the apparatus hereinbefore described is as follows:—Assume the

parts to be in the position shown in Fig. 2, if now the nozzle g^2 be opened as shown and immersed in liquid and the piston e is moved from the position shown in the said figure to that shown in Fig. 9, by the rotation of the hand wheel i^1 , a vacuum will be formed in the cylinder a by the piston b and the cylinder d will simultaneously be filled with liquid by the piston e . A seal is provided between each piston and the end of its chamber by an annular flange a^1 which operates with an elastic seating a^2 .

When the notches k' in the boss k are engaged by the pawls k^2 as hereinbefore described, the pistons b and e will be held and the screw extension rod h of the piston rod e^1 can be unscrewed from the piston e and removed, the said rod being placed in a tubular housing n adapted to receive it. The pistons b and e are held tightly against the seating a^2 thereby preventing access of air to the peripheries of the said pistons until such time as the apparatus is required for use when it is only necessary to press against the hand wheel i^1 with sufficient force to cause the lugs l' to disengage the pawls k^2 from the notches k' when the atmospheric pressure which enters through the angle pipe f^1 , and the orifice d^2 will act upon the pistons b and e , and cause their movement and the ejection of the liquid through the nozzle g^2 .

In both of the foregoing arrangements it is assumed that the vacuum is to be produced either by a direct pull or by hand operated mechanism. Such an arrangement, however, would necessarily limit the application of the invention, and I therefore in Figs. 10 to 12 illustrate the construction of an apparatus which can be operated by power derived from an external source.

In these figures 1 indicates the cylinder, and 2 the partition therein dividing it into two chambers 3 and 4. 5 and 6 are respectively the two pistons sliding in the said chambers 3 and 4 and connected tandemwise by the rod 7 so that they can move simultaneously. The chamber 3 is designed to have the air exhausted from it and the chamber 4 to be filled with water or other liquid when the piston 6 is moved from the position shown in Fig. 10 to that shown in Fig. 12, the liquid being drawn from any suitable source through a pipe 8 which also serves for the discharge of the liquid when the apparatus is used for extinguishing purposes. The liquid can, however, be filled into the chamber in any other convenient manner. 9, 10 are the orifices for the discharge of the air from the chambers 3, 4, respectively, when the pistons 5, 6 are moved as described. To enable such movement of the pistons to be effected the piston 5 may be actuated by compressed air passed through an orifice 11 controlled by a screw operated valve 12, the

air being subsequently exhausted from the chamber 3 by connecting the valve to a suitable vacuum producing source so that the atmospheric pressure can be subsequently exerted above the pistons 5 and 6 to force them down and cause the piston 6 to eject the liquid in the chamber 4. It will of course be understood that after the exhaustion of the chamber 3 the valve 12 is closed.

10 For holding or locking the pistons 5 and 6 in the raised position till it is required to eject the liquid I advantageously provide the following means. On the upper side of the piston 6 is a boss 13 having notches 14, 14 with which engage sliding spring pawls 15 in a casing at the upper end of the chamber 4, as clearly shown in Fig. 12. Adjacent to the said pawls is a disk 16 provided with an external handle 17 and with an interior web 18 having inclined edges which coöperate with the pawls in such a manner that when the handle 17 is pushed inward against the pressure of a spring 19 the pawls will be pushed apart and disengaged from the notches 14, 14 to release the piston 6 so that the atmospheric pressure on the pistons 5 and 6 will move the said piston 6 and eject the liquid through the pipe 8. A slot 20 is formed in the boss 13 to allow the web 18 to engage with and separate the pawls as described, and in order to prevent the pistons 5 and 6 from turning so that the said slot is out of position with relation to the web, the piston rod 7 is made hollow and provided 35 with a square guide 21 which slides upon a square rod 22 attached to the lower end of the cylinder 1.

Although I have described my invention as applied for the discharge of liquids, it is 40 to be understood that it is equally applicable for the discharge of gases or other fluids, or of solid bodies, for instance, projectiles.

Claims:

1. Apparatus for discharging liquid, 45 gaseous or solid bodies by means of atmospheric pressure, comprising two chambers isolated from one another, means whereby a vacuum can be maintained in one chamber and a body to be discharged introduced into 50 the other chamber and pistons in the two chambers connected to move in unison.

2. An apparatus for discharging liquid, 55 gaseous or solid bodies by means of atmospheric pressure, comprising two chambers isolated from one another, and means connected together for simultaneously creating a vacuum in one of said chambers and introducing a body to be discharged into the other chamber, said means being acted upon by

atmospheric pressure to discharge the body 60 in the latter chamber.

3. Apparatus for discharging liquid, gaseous or solid bodies by means of atmospheric pressure, comprising two chambers isolated from one another, means whereby 65 a vacuum can be maintained in one chamber and a body to be discharged introduced into the other chamber, pistons in the two chambers connected to move in unison and means for locking the said pistons against movement under atmospheric pressure, substantially as described.

4. An apparatus for discharging liquid, gaseous or solid bodies comprising two chambers isolated from one another, a piston 75 mounted in each of said chambers connected to move in unison, means for operating said pistons whereby a vacuum will be created in one of said chambers while a body to be discharged is drawn into the other chamber, 80 and means for locking said pistons against movement under atmospheric pressure.

5. An apparatus for discharging liquid, gaseous or solid bodies comprising two chambers, one of which is open to the atmosphere at each end, pistons mounted in each of said chambers, means connecting said pistons for joint movement, means for moving said pistons in one direction for drawing a body into the chamber having open ends and 85 creating a vacuum in the other chamber, a boss connected to one of said pistons and provided with notches, and spring pawls mounted on one of said chambers adapted to enter the notches of the boss for locking the 90 pistons against movement under atmospheric pressure.

6. An apparatus for discharging liquid, gaseous or solid bodies, comprising two chambers, one of which is open to the atmosphere at each end, pistons mounted in each of said chambers, means connecting said pistons for joint movement, means for moving said pistons in one direction for drawing a body into the chamber having open ends and 100 creating a vacuum in the other chamber, a boss connected to one of said pistons and provided with notches, spring pawls mounted on one of said chambers adapted to enter the notches of the boss for locking the 105 pistons, and means for preventing said pistons from rotating whereby the notches will be guided into engagement with the pawls.
